GOLF BALL

Leonard A. Young, Detroit, Mich.

Application June 8, 1931, Serial No. 542,848

5 Claims. (Cl. 273—62)

The main objects of this invention are:

First, to provide a golf ball having a long true "carry".

Second, to provide a golf ball having the above mentioned advantage which has a soft "feel" of the club.

Third, to provide a golf ball having an even roll in putting.

Fourth, to provide a method of making golf balls and cores therefor by means of which the results above set forth may be obtained.

Objects pertaining to details and economies of my invention will definitely appear from the description to follow. The invention is defined in the claims.

A structure embodying the features of my invention and made by the method is clearly illustrated in the accompanying drawing, in which:

Fig. 1 is a fragmentary section of a golf ball embodying the features of my invention, no attempt being made to show the parts in exact dimensions and certain parts being shown conventionally.

Fig. 2 is an enlarged fragmentary section showing further details of the structure.

Fig. 3 is a fragmentary section illustrating one of the steps in the manufacture of the winding core of my improved golf ball.

Fig. 4 is a fragmentary section of one of the sections used in forming the winding core.

Referring to the drawing, my improved golf ball comprises a winding core designated generally by the numeral 1, a winding 2 of resilient strands and an outer casing 3. The winding and the casing are shown conventionally. The elastic strands are wound upon the core under very considerable tension but this step is well understood in the art. The casing or outer shell is also shown conventionally as the methods and means now in use may be employed for applying this outer casing.

My improved winding core comprises a spherical center weight 4 of metal such as lead, steel, copper, or some composition which has the desired specific gravity, and it is also contemplated that it shall be substantially unyielding. This center-weight is disposed centrally of a winding core shell or winding core proper 5 which is formed of rubber and has walls of sufficient thickness to sustain the pressure of a gaseous fluid within the same. This core wall 5 is a true sphere and is of an internal diameter substantially greater than the center weight, providing a space 6 for the gaseous fluid under pressure.

To maintain the center weight in a central posi-

tion the core 5 is provided with internal web-like spacing members 7 preferably integral with the core. The shell has a thin sheath of rubber 8 thereon to which the spacing members 7 are joined by vulcanizing or curing step.

In manufacture the sections 9 are molded preferably in hemispheric form. These are placed within a curing mold, the sections of which are indicated at 10 and 11, Fig. 3, the center weight with its rubber sheath having been placed within the shell. The curing mold is then closed and the curing operation performed which unites the sections, forming in effect an integral winding core. The means for introducing the air or other gaseous fluid under pressure is not illustrated.

The gaseous fluid may be introduced by means of a needle-like nozzle which is withdrawn as the curing mold is closed. Another means of obtaining the fluid pressure is to place within the core a material which is gasified by the vulcanizing or curing heat.

In the further steps of manufacture this core is frozen to render non-yielding and is then wound with the elastic strands under pressure, and the casing is applied. The two latter steps may be performed in accordance with present practice.

My improved golf ball is very responsive and has a long true "carry". It is also very desirable for putting and has the soft "feel" which is sought for in golf balls. While it is recognized that the entire weight of the ball shall not exceed the standard or determined amount, the applicant by this arrangement is able to provide a distinct center of gravity and at the same time have an air or gaseous cushion so that the ball is very responsive and at the same time true in its action.

Having thus described my invention what I claim as new and desire to secure by Letters Patent is:

1. A golf ball comprising a spherical center weight of metal, a thin encasing sheath of rubber on said center weight, a winding core shell consisting of a pair of complementary hemispherical sections having internal web-like inwardly tapered ribs extending longitudinally between common poles of the sections and fitting said sheath to center said weight within the core and dividing the space between the shell and sheath into a plurality of individual longitudinal cells for the reception of gaseous fluid under pressure, the parts being vulcanized to form an integral whole and to render said cells individually fluid-tight, and a winding of resilient rubber strands on said

core shell and having a radial thickness greater than that of the shell.

2. A golf ball comprising a spherical center weight of metal, a thin encasing sheath of rubber on said center weight, and a winding core shell consisting of a pair of complementary hemispherical sections having internal web-like inwardly tapered ribs extending longitudinally between common poles of the sections and fitting said sheath to center said weight within the core and dividing the space between the shell and sheath into a plurality of individual longitudinal cells for the reception of gaseous fluid under pressure, the parts being vulcanized to form an integral whole and to render said cells individually fluid-tight.

3. A golf ball comprising a spherical center weight, a thin encasing sheath of rubber on said center weight, and a core shell having internal web-like, inwardly tapered ribs extending longitudinally between common poles of the sections and united with said sheath to center said weight within the core and dividing the space between

the shell and sheath into a plurality of individual fluid-tight longitudinal cells for the reception of gaseous fluid under pressure.

4. In a golf ball, a spherical center weight of metal, means surrounding and centering said weight comprising a rubber sheath and a winding core shell having internal web-like longitudinal inwardly tapered ribs, said ribs being integrally joined to said sheath at their inner ends whereby a plurality of individual fluid-tight cells are formed, a gaseous fluid under pressure in said cells, and a winding of resilient strands on said core shell.

5. In a golf ball, a spherical center weight, means surrounding and centering said weight comprising a sheath and a winding core shell having internal web-like longitudinal ribs, said ribs being integrally joined to said sheath at their inner ends whereby a plurality of individual fluid-tight cells are formed, and a gaseous fluid under pressure in said cells.
